UNITED STATES PATENT OFFICE.

GEORGE BOTSCHEIDER, OF SAN FRANCISCO, CALIFORNIA.

ELEVATOR-CONTROL SYSTEM.

1,409,132.

Specification of Letters Patent.

Patented Mar. 7, 1922.

Application filed April 5, 1920. Serial No. 371,398.

To all whom it may concern:

Be it known that I, GEORGE BOTSCHEIDER, a citizen of the United States, and a resident of the city and county of San Francisco, State of California, have invented a certain new and useful Elevator-Control System, of which the following is a specification.

The invention relates to elevator control systems and particularly to systems for limiting the movement of the lever which controls the movement of the car when the elevator door is unlocked or open.

An object of the invention is to provide means for holding the elevator control lever to limited movement when the elevator door is unlocked or open.

Another object of the invention is to provide means for simultaneously unlocking the elevator door and imposing a barrier to the movement of the control lever.

The invention possesses other advantageous features, some of which, with the foregoing, will be set forth at length in the following description where I shall outline in full, that form of the invention which I have selected for illustration in the drawings accompanying and forming part of the present specification. In said drawings, I have shown several specific forms of the apparatus of my invention, but it is to be understood that I do not limit myself to such forms, since the invention, as set forth in the claims, may be embodied in a plurality of other forms.

Referring to said drawings:

Figure 1 is a section of an elevator shaft having a car therein provided with one form of apparatus of my invention.

Figure 2 is a section of an elevator shaft having a car therein provided with a modified form of apparatus of my invention.

Figure 3 is a section of an elevator shaft showing an electric elevator provided with a modified form of apparatus of my invention.

Figure 4 is a detail of the lock bar used in the construction shown in Figure 3.

The apparatus of my invention is applicable to hydraulic and electric elevators, with equal efficiency, and operates to limit the movement of the control lever of the elevator car, when an elevator door is unlocked or open. The permitted movement

of the control lever is sufficient only to maintain the car at the floor from which it may slip due to leakage or to permit a very slow movement of the car to bring it into alignment with the floor.

In the arrangement shown in Figure 1, means are provided for limiting the movement of the control lever when the door is open, either partly or wholly. The control lever 2 is normally movable to either side of the vertical or neutral position, to control the elevator motor to cause the car to ascend or descend. The lever is usually disposed in a housing 3 having a slot in the top in which the lever moves. Mounted on the housing is a vertically movable slide 4 having a head 5 provided with a seat or depression 6 therein, which head is normally disposed below the path of a pin or projection 7 on the lever. The seat 6 is of less length than the throw of the projection 7 and when the slide is elevated, the projection 7 is disposed in the seat, so that the lever is capable of limited movement only in either direction. In a hydraulic elevator, the amount of movement of the lever is sufficient to overcome any creeping of the car due to leaky valves, and in electric elevators the amount of movement of the lever is sufficient to produce a very slow movement of the car. In the construction shown in Figure 1, the slide 4 is raised by the opening movement of the elevator door 8 and is held raised during the time that the door is opened. Secured to the door 8 is a bar 9 having an inclined end 10, which when the door is closed, lies under the roller 12 on the bent lever 13 and as the door is opened the roller moves up over the incline onto the high surface of the bar 9, rocking the lever 13 on its pivot. The other end of the lever is provided with a roller 14, which lies in position to be engaged by the movable cam 15, pivotally mounted on the elevator car. The cam 15 is mounted on two levers 16, so that it is movable laterally while retaining its vertical position. Pivoted to the levers 16 is a link 17 which is connected to the slide 4 by suitable means, such as the bell-cranks 18 and 19 and the link 21. When the car comes to rest at a floor, the roller 14 is in contact with the cam 15 and the opening movement of the door causes the lever 13 to push the cam 15 backward, raising the slide 4 and hold-

ing the control lever to limited movement. The control lever is held in this position until the door is again fully closed.

In the construction shown in Figure 2, 5 means are provided for causing the unlocking of the door to limit the movement of the control lever. In this construction the bar 9 is provided with a notch into which the end of the locking lever 22 falls, to lock the door 10 in the closed position. The locking lever 22 is provided on its other end with a roller 23 which lies in the path of guideway formed between the two guides 24, the two guides being secured together forming a guide 15 structure. This structure is mounted on the levers 25, so that it is movable laterally while maintaining its vertical position. The levers 25 are pivoted to the link 26 which extends 20 downward, the lower end of the link lying below the car floor 27. The link is provided with a handle 28 for moving it vertically and at its lower end is suitably connected to the slide 4. Movement of the link in a direction to unlock the bar 9 raises the slide 4 to 25 a position to restrict the movement of the control lever 2. With the initial opening movement of the door, the bent lever 13 is actuated to move the cam 15 and the link 17. The link 17 is connected to the slide 29 which 30 is moved under the lower end of the raised slide 4, thereby preventing the slide from being lowered as long as the door is open.

The construction shown in Figure 3 shows the application of the invention to an electric elevator. In this construction the link 26 is moved vertically to release the locking lever 22, as in the construction shown in Figure 2. The control lever 31 is secured to a gear 32 which meshes with a rack on the rod 33 which extends downward through the floor of the car, where the rod is provided with two spaced cylindrical enlargements 34-35. Connected to the link 26, in such manner that it is moved longitudinally by 40 vertical movement of the link, is a controller lock bar 36. This bar is provided with a hole 37 which is larger than and normally aligned with the enlargements 34-35 so that the enlargements may readily pass through the 45 hole as the controller lever is moved. The bar is also provided with smaller apertures or slots 38 extending longitudinally from and communicating with the hole 37. When the 50 control lever is in neutral position, the enlargements lie on opposite sides of the bar 55 and the unlocking of the door moves the bar longitudinally so that the rod 33 is dis-

posed in a slot 38 which is too small to permit the enlargements to pass. The enlargements are spaced apart sufficiently to permit 60 a limited movement of the control lever.

I claim:

1. The combination with an elevator shaft, a door on said shaft, a car in said shaft and a controlling lever in said car, of a cam carried by the car, a door lock cooperable with said cam, means operable independently of the lever, for actuating the cam to unlock the door, and means connected to said actuating means for limiting the movement of 70 said lever, and including a plate having a key hole, and a locking pin connected to the lever.

2. The combination with an elevator shaft, a door on said shaft, a car in said shaft and a controlling lever in said car movable to either side of a neutral position, of a shaft connected to said lever, spaced enlargements on said shaft connected by a narrow neck and a plate having a key hole therein associated with said shaft and cooperating with said enlargements said shaft passing through said key hole and means for moving said plate to lock the lever in neutral position.

3. The combination with an elevator shaft, a door on said shaft, a car in said shaft and a controlling lever in said car movable to either side of a neutral position, of a shaft connected to and movable with said lever, spaced enlargements on said shaft, a plate 85 slidable at right angles to said shaft and having an aperture therein flanked by two slots opening into the aperture, so that the shaft may be moved longitudinally only when the aperture is aligned with the shaft 95 and the plate may be moved only when the enlargements lie on opposite sides of the plate and means connecting the plate with the door locking mechanism.

4. The combination of an elevator car 100 having a controlling lever movable from neutral to operative positions, a door operatively arranged at a doorway in the traverse of the said car, a door lock, a cam carried by the car and co-operative with said lock, and a cam operating mechanism on the car and independent of the control lever when the latter is in the neutral position for actuating said cam to unlock the door and including means for locking the lever in the neutral 110 position when the door is unlocked.

In testimony whereof, I have hereunto set my hand.

GEORGE BOTSCHEIDER.
